UNITED STATES PATENT OFFICE.

JACOB C. MARKMAN, OF AMSTERDAM, NEW YORK, ASSIGNOR TO FULTON COUNTY MACHINE AND SUPPLY COMPANY, OF GLOVERSVILLE, NEW YORK, A CORPORATION OF NEW YORK.

ATTACHMENT FOR FAST-WARP KNITTING MACHINES.

Application filed November 10, 1920, Serial No. 423,049. Renewed April 7, 1922. Serial No. 550,509.

To all whom it may concern:

Be it known that I, JACOB C. MARKMAN, a citizen of the United States, residing at Amsterdam, in the county of Montgomery and State of New York, have invented a new and useful Attachment for Fast-Warp Knitting Machines, of which the following is a specification.

This invention has reference to knitting machines of the kind used in making silk and cotton jersey cloth for gloves, and also in making silk and cotton nets and which may be used for making cotton atlas cloth afterward finished to imitate chamois, and then called chamoisette.

Such knitting machines are known in the practical art, by various names, such as "fast warp," "traverse warp" and "flat bar" knitting machines.

20 In machines used for the purposes named, difficulty has been found in properly constructing the pattern wheels, because, as heretofore made, the pattern arm is actuated by the pattern wheel in such a manner that there is either a lead or a lag between the pattern wheel and the part engaged thereby, through which motion is transmitted to the pattern arm by way of the customary connections.

30 In accordance with the invention, push rods are employed having a path or reciprocation always radial to the pattern wheel, and then the motion is translated into another motion perpendicular to the direction of travel of the push rod. Such change of motion has heretofore been proposed, but at the point of translation of the motion, curvilinear motion has been included, thus introducing certain difficulties making it

40 necessary to correct the pattern wheels in a manner necessitating hand work thereon, and introducing other errors. It is the purpose of the invention to provide a translating motion which will eliminate the necessity of hand work and attendant errors so that the mechanism employed may be properly calculated as to its proportions and accurately machined, whereby all liability of acceleration and lag is done away with, and 50 the quality of the work performed by the machine materially improved. For this purpose the translating motion occurs through rack and pinion connections at right angles to each other with the rack movements

straight and constant in speed throughout 55 their travel, instead of the movements being through the intermediary of rock levers and in curved paths.

The invention will be best understood from a consideration of the following detailed description taken in connection with the accompanying drawings forming part of this specification, with the understanding, however, that the invention is not confined to any strict conformity with the showing 60 of the drawings, but may be changed and modified so long as such changes and modifications mark no material departure from the salient features of the invention as expressed in the appended claims. 70

In the drawings:

Fig. 1 is a side elevation of the part of the machine containing pattern wheels and associated mechanism.

Fig. 2 is an end elevation, with some parts 75 in section of the structure of Fig. 1 as seen from the left-hand end thereof.

Fig. 3 is a plan view of the structure shown in Fig. 1.

Fig. 4 is a section on the line 4-4 of 80 Fig. 2.

Fig. 5 is a section on the line 5-5 of Fig. 4.

Fig. 6 is a perspective view of one of the rack and pinion structures. 85

Referring to the drawings, there is shown in Fig. 1 a portion 1 of the main frame of the knitting machine to which the invention is applied. Fast to the frame 1 are spaced brackets 2 carrying a shaft 3 on which there 90 is secured a toothed wheel 4 engaged by flanges or wings 5 on a wing wheel 6 which is mounted on a drive shaft 7 receiving motion from a suitable source of power, not shown, and assumed to be supported on the 95 main frame of the machine in a manner also not shown, since the shaft and wing wheel form no part of the invention. The purpose of the wing wheel 6 and toothed wheel 4 is to impart a rotary step-by-step movement to the shaft 3 with the steps relatively short, a commercial form of the invention requiring say 96 impulses of the wheel 4 to make one complete revolution thereof and of the shaft 3. 100

Fast to the shaft 3 are pattern wheels 8 9 respectively, there being two such wheels suitably spaced apart in the showing of the

drawings. The pattern wheels are in eccentric relation to the axis of rotation of the shaft 3, and each wheel has a continuous series of teeth 10 on its periphery.

5 Engaging each pattern wheel 8 and 9, is a vertical rack bar 11 individual to the respective pattern wheel and provided at its lower end with a roller 12 riding on the teeth 10 so as to be actuated by said teeth 10 as the pattern wheel rotates and so that the rack bar besides having impulses imparted to it corresponding to the teeth 10, also has a slower and more extended movement imparted to it by the eccentric or 15 cam form of the pattern wheel. Each rack bar 11 has a series of gear teeth 13 on one edge meshing with one end of an elongated gear pinion 14 long enough to engage a series of gear teeth 15 on another rack bar 20 16 capable of traveling alongside of and perpendicular to the direction of travel of the rack bar 11. The teeth on the rack bars and on the pinion 14 are so proportioned that the rack bars move simultaneously in right- 25 angular relation, the movement of the rack bar 11 being vertical and the movement of the rack bar 16 being horizontal in the installed position of the parts. In order to protect and guide the rack bars and also 30 protect and support the pinion 14, these parts are inclosed in a housing 17 of sufficient extent to inclose the rack bars and gears belonging to both pattern wheels. The housing 17 is a stationary housing 35 which may be fixedly attached by a bracket 18 to one of the frames 2.

Each horizontal rack bar 16 is made fast to an adjustable guide bar 19 of the machine, such adjusting bars having adjusting screws 20 whereby their effective length 40 may be established. The guide bars 19 are shown in Fig. 3 as being each connected to one end of an extension spring 21.

When the machine is in operation, the 45 shaft 7 is driven by suitable power, rotating the wing wheel 6, and thereby imparting step-by-step rotary movement to the gear wheel 4, and through the latter to the shaft 3. The two pattern wheels participate in 50 the rotary movement of the shaft 3 and radial impulses are imparted to the rack bars 11 in alternation. At the same time a slower reciprocating movement is imparted to the rack bars 11 in alternation because 55 of the cam form of the pattern wheels. The reciprocating movement of each bar 11 is translated into an oscillatory movement of the respective pinion 14 which latter, being in mesh with the companion rack bar 16, 60 causes the latter to correspondingly reciprocate. The gear wheel 14, being in mesh with the rack bar 16, causes the latter to reciprocate in unison with the rack bar 11. In one direction of movement of the rack bar 65 16, the corresponding spring 21 is extended,

motion being imparted to parts of the machine not shown and at the time of the extension of the spring 21, the rack bar 11 is being forced upwardly by the cam formation of the respective pattern wheel. As 70 the pattern wheel 8 or 9 continues its rotary movement, the low portion of the pattern wheel is reached and the extended spring 21 then acts to cause the rack bar 11 to follow up such low part of the pattern 75 wheel. In this way the gear teeth 13, 14 and 15 maintain their engagement always on the same faces, so that the engagement is constant and the wear is uniform.

The new rack attachment works in 80 straight lines instead of the engaging parts moving in arcs. This eliminates all losses and gains, all levers and the necessity of hand fitting. The height of each step on the pattern wheel is thus known, where- 85 fore, the pattern wheel may be accurately machined or milled ready for use, with the result that the machine is thoroughly and accurately equipped and produces a better quality of fabric than has heretofore been 90 attained.

What is claimed is:

1. In a knitting machine of the type de- 95 scribed, the combination with the guide bars of the machine, of eccentrically arranged pattern wheels, radially movable rack bars engaged by the pattern wheels, a pinion for each rack bar; other rack bars meshing with the pinions and movable in paths at right angles to the first-named rack bars, and connections between the second-named rack bars and the guide bars.

2. In a knitting machine of the type de- 105 scribed, the combination with the guide bars of the machine of eccentrically arranged pattern wheels and connections between the pattern wheels and the guide bars for translating the eccentric movement of the pattern wheels into straight line reciprocatory movements of the guide bars, the translating 110 movements being in angularly related right lines.

3. In a knitting machine of the type de- 115 scribed, the combination with the guide bars of the machine movable in straight lines, of eccentrically arranged pattern wheels, rack bars movable in right lines by and radial to the pattern wheels and motion-translating mechanism between the rack bars and the guide bars comprising pinions engaged by 120 the rack bars and other rack bars engaged by the pinions and movable by the latter in directions at right angles to the movement of the first-named rack bars, whereby the transitory movements between the pattern 125 wheels and the guide bars are straight and at right angles to each other.

4. In a knitting machine of the type de- 130 scribed, the combination with the guide bars of the machine, movable in straight lines, of

- eccentrically arranged pattern wheels, rack bars movable in right lines by and radial to the pattern wheels, and motion-translating mechanism between the rack bars and the 5 guide bars comprising pinions engaged by the rack bars and other rack bars engaged by the pinions and movable by the latter in directions at right angles to the movement of the first-named rack bars, whereby the 10 transitory movements between the pattern wheels and the guide bars are straight and at right angles to each other, the rack bars crossing each other at right angles side by side and each pinion being elongated so that its teeth will engage both rack bars simultaneously, and a housing inclosing the pinions and also 15 inclosing the rack bars where crossing, and serving as a guide and support for the rack bars.
6. In a knitting machine of the type described, the combination with the guide bars of the machine, with each guide bar provided with a spring constraining it to move in one direction, of eccentrically arranged pattern wheels, a rack bar for each pattern wheel movable in a direction radial to the pattern wheel, another rack bar connected to 20 each guide bar and movable therewith at right angles and adjacent to the first-named rack bar, and an elongated pinion simultaneously engaging the teeth on both rack bars, whereby the rack bars are constrained to 25 move together to extend the spring in one direction of movement and to respond to the spring in the opposite direction of movement.
5. In a knitting machine of the type described, the combination with the guide bars of the machine movable in straight lines, of eccentrically arranged pattern wheels, rack bars movable in right lines by and radial to the pattern wheels, and motion-translating mechanism between the rack bars and the guide bars comprising pinions engaged 25 by the rack bars and other rack bars engaged by the pinions and movable by the first-named rack bars, whereby the transitory movements between the pattern wheels and the guide bars are straight and at right angles to each other, the rack bars crossing each other at right angles side by side and each pinion being elongated so that its teeth will engage both rack bars simultaneously, and a housing inclosing the pinions and also 30 inclosing the rack bars where crossing, and serving as a guide and support for the rack bars.
6. In a knitting machine of the type described, the combination with the guide bars of the machine, with each guide bar provided with a spring constraining it to move in one direction, of eccentrically arranged pattern wheels, a rack bar for each pattern wheel movable in a direction radial to the pattern wheel, another rack bar connected to 35 each guide bar and movable therewith at right angles and adjacent to the first-named rack bar, and an elongated pinion simultaneously engaging the teeth on both rack bars, whereby the rack bars are constrained to move together to extend the spring in one direction of movement and to respond to the spring in the opposite direction of movement.
- In testimony, that I claim the foregoing as my own, I have hereto affixed my signature.

JACOB C. MARKMAN.
